UNITED STATES PATENT OFFICE.

REINHOLD MILKE, OF SAN FRANCISCO, CALIFORNIA.

GAS-TURBINE.

1,277,626.

Specification of Letters Patent. Patented Sept. 3, 1918

Application filed February 20, 1917. Serial No. 149,876.

To all whom it may concern:

Be it known that I, REINHOLD MILKE, a citizen of the United States, residing at San Francisco, in the county of San Francisco, 5 State of California, have invented certain new and useful Improvements in Gas-Turbines; and I do hereby declare the following to be a full, clear, and exact description of the invention; such as will enable others 10 skilled in the art to which it appertains to make and use the same.

This invention relates to internal combustion engines and has special reference to a gas turbine.

15 One important object of the invention is to provide an improved simplified general construction of a device of this character.

A second important object of the invention is to provide an improved means for 20 controlling the flow of a combustible mixture to an explosion chamber used in connection with a device of this character.

A third important object of the invention is the provision of an improved form of 25 feeding valve for use between the storage chamber for the compressed mixture and the explosion chamber in a device of this description.

With the above and other objects in view, 30 as will be hereinafter apparent the invention consists in general of certain novel details of construction and combinations of parts hereinafter fully described, illustrated in the accompanying drawing, and specifically 35 claimed.

In the accompanying drawing, like characters of reference indicate like parts in the several views, and :-

Figure 1 is a vertical median section 40 through this invention.

Fig. 2 is a section on the line 2-2 of Fig. 1.

Fig. 3 is a section on the line 3-3 of Fig. 1.

45 Fig. 4 is an enlarged detail section on the line 4-4 of Fig. 1.

Fig. 5 is an enlarged detail section on the line 5-5 of Fig. 1.

Fig. 6 is an elevation of the left hand end 50 portion of the structure shown in Fig. 1.

Fig. 7 is a section on line 7-7 of Fig. 1, looking to the left.

Fig. 8 is a section on line 8-8 of Fig. 2, looking to the left.

55 In the embodiment of the invention herein illustrated there has been provided a casing

10 and on this casing 10 are located radially arranged cylinders 11, there being preferably four of these cylinders. These cylinders form compression cylinders and in each 60 of the cylinders is a piston 12 which reciprocates in the cylinders and alternately covers and uncovers an intake port 13.

Journalled in the casing 10 is a drive shaft 14 and fixed upon this drive shaft is a cam 65 15 preferably elliptical in contour and having a T-shaped slot 16 in its peripheral edge. In the broad portion of the slot 16 are located the heads 17 of piston rods 18, the stems of the rods passing out of the slot 70 through the narrow portion of the same. These heads 17 are preferably circular in contour and are provided with suitable ball bearings 18' so that the heads may move freely in the slot 16.

75 Each of the cylinders 11 is provided in its head with a chamber 19 which communicates with the body of the cylinder through a port 20 controlled by a pocket valve 21 having a stem 22. This stem 22 is received in a guide boss 23 wherein it is slidable and covering the outer end of this guide boss is an adjusting screw 24. A spring 25 is located between each of the adjusting screws 80 or caps 24 and the outer end of the respective stem 22. Now it will be noted that by means of the adjustment of the cap 24 the 85 attention of the respective spring 25 may be varied at will so as to exert a greater or less degree of pressure on the end of the stem 22 90 and thus hold the valve 21 in position with a greater or less force.

95 In the operation of this part of the device it will be observed that as the shaft 14 rotates the cam 15 will also rotate and this will effect reciprocation of the pistons 12. As these pistons move inward the valve 21 will close the port 20 and a partial vacuum will be forced in each of the cylinders 11. As soon as the respective piston uncovers the port 13, this port being connected to a suitable carbureter, (not shown) the explosive mixture will rush in through the port and fill the cylinder. The piston 12 in each cylinder after reaching its farthermost inward movement will then move outward and close the port 13, subsequently compressing the charge in the outer end of the cylinder. This will force open the valve 21 so that the compressed charge will pass into the chamber 19.

100 105 110 115 In the casing 10 is formed an annular re-

ceiving chamber 26 for the compressed mixture and this chamber communicates with the several chambers 19 through ports 27 so that as the successive charges are received 5 in the chambers 19 these compressed charges will pass out of the chambers 26 through the ports 27 and into the receiving chamber 26. In the casing 10 is a turbine wheel compartment 28 wherein is located a turbine wheel 10 29 which is fixed on the shaft 14 and is provided with peripheral blades 30. Between the chamber 26 and the compartment 28 are located a series of pairs of valve casings 31 each of which communicate through a port 15 32, opening into the side of the casing, with the chamber 26. Leading from the end of each of the casings 31 is a port 33 which communicates with a small chamber 34, each chamber 34 forming a combustion chamber 20 for two of the casings 31. Leading from the chamber 34 is a nozzle 35 which delivers the gases of combustion to the blades 30 as clearly seen in Fig. 1.

Revolubly mounted concentric of the axis 25 of each of the casings 31 is a prismatic valve 36, the shaft of the valve extending through one end of the casing and carrying a pinion 37 which meshes with a gear 38 fixed on the shaft 14. In the form of the invention 30 herein shown the prismatic valve takes the form of a triangular prism having slightly rounded sides and rounded edge angles and these angles contact with the inner surface of the respective casing 31.

35 Slidable radially of each casing 36 is an abutment 39 which moves in guides 40, being constantly pressed inward by means of springs 41. The inner edges of these abutments 39 contact continuously with the 40 valves 36 so that they form a cut-off for the chamber within the casing 31, dividing the chamber into two parts. The outlet ports 33 of the casings 31 are located immediately adjacent the abutments 39 at the sides 45 thereof toward which the valve moves in normal rotation. The said abutments thus serve to clear the successive valve spaces of their fuel vapor contents forcing the fuel vapor into the combustion chambers by closing off the valve spaces as the valves rotate, and preventing passage of the exploded vapor back into the valve casing, whereby the whole force of the explosions is exerted 50 through the flared mouths 35. Fig. 7 shows 55 more clearly the relation of the parts 31 and abutments 39, and it is noted that the explosions are timed to occur prior to and adjacent the time of movement of the peripheral extremities of the valves 36 past the abutments.

Now it will be seen that the action of the valve is such as to feed the compressed mixture from the chamber 26 into the explosion chambers 34 in a continuous succession of 65 small volumes and it will be obvious that

there is provided in each chamber 34 a suitable sparking plug as indicated at 42, an arrangement being made whereby a continuous series of sparks pass between the terminals of such plugs. It is not deemed necessary in the present instance to illustrate any specific arrangement by means of which these sparks may thus be caused to pass as this does not form any particular part of the invention.

75 In order to dispose of the spent gases the chamber 28 is provided with suitable ports 44 through which these gases may pass into an exhaust chamber 45 provided with a suitable exhaust pipe 46.

80 In order to guide the pistons 12 extensions 47 are formed on these pistons and these extensions work between a guide 48 on the walls of the cylinders.

85 There has thus been provided a simple and efficient device of the kind described and for the purpose specified.

90 It is obvious that many minor changes may be made in the form and construction of the invention without departing from the material principles thereof. It is not therefore desired to confine the invention to the exact form herein shown and described but it is wished to include all such as properly come within the scope of the claims.

95 Having thus described the invention, what is claimed as new, is:

1. In a gas turbine, a cylindrical valve casing provided with means at spaced points for communication to a compression chamber and an explosion chamber respectively, a prismatic valve rotatably mounted within said casing and having the side edges of the prism in contact with the wall of said casing, a sliding abutment movable transversely of the casing and having its inner edge constantly in contact with the side of the valve, and means to rotate the valve.

with the explosion chamber, a prismatic valve rotatably mounted axially of the casing and having its side edges in contact with the inner surface of the casing, means driven 5 from the turbine wheel and connected to the valve to rotate said valve, and a sliding abutment positioned opposite the inlet and movable radially toward and from the center of the casing, the inner edge of said

abutment being constantly in contact with 10 the prismatic valve.

In testimony whereof, I affix my signature, in the presence of two witnesses.

REINHOLD MILKE.
